UNITED STATES PATENT OFFICE.

SWAN E. MOREN, OF BIWABIK, MINNESOTA.

BRIQUET-MACHINE.

1,384,206.

Specification of Letters Patent. Patented July 12, 1921.

Application filed December 23, 1920. Serial No. 432,747.

To all whom it may concern:

Be it known that I, SWAN E. MOREN, a citizen of the United States, residing at Biwabik, in the county of St. Louis and State of Minnesota, have invented certain new and useful Improvements in Briquet-Machines, of which the following is a specification.

This invention relates to briquet machines and has special reference to machines of the type shown in Letters Patent No. 1,306,309, granted to me June 10, 1919, the object of the present improvements being to increase the efficiency of the apparatus and simplify the construction and operation.

15 The invention is illustrated in the accompanying drawings, in which—

Figure 1 is a perspective view showing a gang of machines embodying the invention; Fig. 2 is a view, partly in longitudinal section and partly in side elevation, showing the position of the parts prior to the compressing operation;

Fig. 3 is a longitudinal section showing the parts in the position assumed during the compressing operation;

Fig. 4 is a similar view showing the parts arranged to permit discharge of a formed briquet;

30 Figs. 5, 6 and 7 are detail views.

Referring more particularly to Fig. 1 there is shown a supporting frame which may be of any substantial construction and, as illustrated, consists of a plurality of posts 35 1 upon which are secured beams 2 in parallel relation. Supported upon the beams and extending between the same are a series of bodies 4 in each of which a compressing mechanism is mounted and in rear of the several bodies a driving shaft 5 extends longitudinally of the frame and is connected through gears 6 with a crank shaft 7 operatively connected with the working members of each compressing mechanism. Above the several bodies, a trough 8 extends longitudinally of the frame and in the bottom of this trough is a conveyer 9 by which the material is fed to a series of spouts 10 and delivered through said spouts to hoppers 11 on the respective bodies 4, as shown and as will be readily understood. The return run of the conveyer 9 is disposed below the several bodies and between the said return run and the discharge openings of the bodies is a 55 conveyer 12 for carrying off the formed bricks. These conveyers may be of any pre-

ferred or convenient construction and will, of course, be operated by any preferred mechanism.

Each body 4 comprises side rails connected 60 at their forward ends by an abutment 13 and at their rear ends by a pillar 14 which is of less height than the abutment 13, the side bars immediately adjacent the pillar 14 supporting bearings 15 in which the main driving shaft 5 is journaled. Secured to the abutment 13 in any convenient manner is a stationary cylinder 16 having longitudinal slots 17 in its sides at its front end, the rear end of the cylinder having its wall beveled, 70 as shown most clearly at 18 in Fig. 4 for a purpose which will presently appear, and adjacent the rear end of the cylinder 1 form within the circular wall of the cylinder a steam space 19 which may be supplied with 75 steam in any convenient manner, but is shown as communicating through a hose 20 with the steam jacket 21 of the movable cylinder 22, a drain cock 23 being provided so that the water of condensation in the jacket 80 19 may be withdrawn when necessary. Within the cylinder 16 is closely but slidably fitted a jaw 24 having its rear end 25 concave so as to receive and shape the material from which the brick is to be formed 85 and at the front end of this jaw 24 I provide the laterally extending diametrically opposite lugs 26 which are adapted to play in the slots 17 of the cylinder 16, as will be readily understood.

90 The reciprocating cylinder 22 carries the hopper 11 and the wall of said cylinder and of said hopper is hollow and forms a part of the steam jacket 21 to which steam is admitted through a supply pipe or hose 27. 95 At the rear end of the cylinder 22 are diametrically opposite guide lugs 28 which rest upon the upper walls of the recesses 29 formed in the side rails of the respective bodies 4 and are held to said bases by cap plates 30 100 secured upon the side rails in an obvious manner. The front extremity of the cylinder 22 is beveled, as shown at 31, reversely to the bevel 18 of the stationary cylinder 105 so that when the cylinders are brought together a close joint will be formed, leakage of material will be prevented, and all the material fed into the cylinder through the hopper will be compressed and a briquet of the desired size and weight will be produced. To reciprocate the cylinder 22, a 110 rack 32 is formed on the under side thereof

and this rack is engaged by a segmental gear 33 on the upper end of an oscillatory arm 34 which is pivotally suspended from the side members of the body 4. The lower 5 end of the oscillatory arm or bar 34 is connected by a link 35 with the lower end of a lever 36 which is fulcrumed upon the body 4 and has its upper end carried rearwardly to be actuated by a tappet 37 on the crank 10 shaft 7 so that the cylinder 22 will be periodically withdrawn from the stationary cylinder 16. A spring 38 attached to the frame and the lower end of the lever 36 holds the parts normally in such position that 15 the two cylinders will be in engagement, as shown in Figs. 2 and 3.

Upon the sides of the cylinder 22, adjacent the end thereof, I provide the lugs 39 having trunnions 40 projecting therefrom 20 and to the lugs 26 I pivotally attach the rear ends of links 41 which extend rearwardly therefrom and are provided with longitudinal slots 42 in their rear ends. The said slots 42 receive the trunnions 40 and 25 thereby constitute a lost-motion connection between the two cylinders. It will be readily understood that during compression the two cylinders are in contact and the block 24 is at the front end of the cylinder 30 16, the trunnions 40 being at the front ends of the respective slots 42, as shown in Fig. 2. When the cylinder 22 moves rearwardly, the trunnions 40 will ride in the slots 42 until they reach the front ends of the slots where- 35 upon the continued movement of the cylinder will draw the links 41 rearwardly and thereby pull the said block 24 rearwardly so that it will eject the briquet and upon the return movement of the cylinder the 40 ejector block will remain in its rearward position until the trunnions 40 engage the front ends of the slots 42 whereupon the ejector block will be returned to its position against the abutment 13.

45 Within the cylinder 22 is mounted a plunger or piston consisting of a front member 43 having its front end recessed, as shown at 44, to impart the desired form to the briquet and a rear member 45 which 50 is coupled to the front member 43 in such manner that the said front member may yield to any large stone or other unyielding elements which may pass into the hopper with the compressible material. The 55 plunger is reciprocated by a pitman 46 engaged upon and actuated by a crank of the shaft 7.

In operation, the plunger is withdrawn to the position shown in Fig. 2 so that material 60 fed into the hopper 11 may pass into the cylinder 22 and be thereby held in front of the plunger. The rotation of the crank shaft 7 will force the plunger forward in the cylinder and the material to be compressed will be thereby pushed against the

receiving jaw ejector block 24 and will be compressed, the parts being so timed that as the plunger recedes the cylinder will also recede so that an open space will be produced between the two cylinders, as clearly 70 shown in Fig. 4, and just before the movable cylinder reaches the rear limit of its movement the block 24 will be drawn rearwardly so that the formed brick will be freed of the stationary cylinder 16 and will drop 75 through the opening between the two cylinders onto the conveyer 12. Immediately after the block has been thus ejected and discharged, the tappet 37 will clear the end of the lever 36 and the spring 38 will return the cylinder 22 to its forward position, whereupon another charge may be delivered 80 thereinto. The rearward movement of the plunger, of course, continues until the front end thereof has cleared the hopper so that 85 there will be no obstruction to the delivery of the material into the cylinder and the return forward movement of the plunger will cut off any additional flow from the hopper.

In my present apparatus, the material 90 which is being compressed is heated through its contact with the hot walls of the two cylinders and is, therefore, more plastic and may be compressed more readily and more firmly than when it is not exposed to the 95 action of a heating agent. Also by my present construction I provide an abutment having a continuous uninterrupted face so that a better finish in the product is attained and the ejecting of the formed brick is more 100 positively effected than by the arrangements heretofore employed. The links constituting the lost-motion connection between the reciprocatory cylinder and the abutment jaw or ejector block are arranged between the 105 cylinders and the side rails of the respective bodies 4 so that they are protected from injury by chance blows and are in operative condition at all times. The present construction is not costly and adds to the efficiency and durability of the apparatus. 110

Having thus described the invention, what is claimed as new is:

1. In a briquet machine, the combination of a stationary cylinder, a reciprocatory cylinder arranged to abut and form a close joint with the stationary cylinder, a combined compressing jaw and ejector block mounted in the stationary cylinder, a plunger slidably mounted in the reciprocatory cylinder, 120 means for reciprocating the plunger and the said cylinder, and means for heating the walls of the two cylinders.

2. In a briquet machine, the combination of a stationary cylinder having a hollow wall, a compressing jaw fitted in said cylinder, a reciprocatory cylinder arranged to abut the stationary cylinder and form a close joint therewith, a plunger mounted in the reciprocatory cylinder to coöperate with 130

the said compressing jaw, a hopper mounted on the reciprocatory cylinder, and means for heating the walls of the two cylinders and the said hopper.

- 5 3. In a briquet machine, the combination of a stationary cylinder, a compressing jaw fitted therein, a jacket formed in the wall of the said cylinder, a hollow-walled reciprocating cylinder mounted to abut and form 30 a close joint with the stationary cylinder, a hollow-walled hopper on said reciprocating cylinder, a flexible connection between the two cylinders establishing communication between the jackets of the same, and 35 15 means for supplying a heating fluid to the jacket of one of the cylinders.
4. In a briquet machine, the combination of a stationary cylinder, a block fitted in said cylinder, a reciprocating cylinder 40 mounted to abut the stationary cylinder and form a close joint therewith, a plunger fitted in the reciprocating cylinder, and a lost motion connection between the reciprocating cylinder and the block in the stationary cylinder. 45
5. In a briquet machine, the combination of a stationary cylinder, a block fitted there- 50 20 25

in and constituting a combined jaw and ejector, guide lugs on said block extending through and guided by the wall of the stationary cylinder, a reciprocating cylinder arranged to abut and form a close joint with the stationary cylinder, a plunger mounted in the reciprocating cylinder to coöperate with the said block, trunnions on the reciprocating cylinder, and links pivoted to the guide lugs on the said block and having longitudinal slots engaging the said trunnions.

6. In a briquet machine, the combination of a stationary cylinder having an open rear end and having its wall beveled around said end, a block fitted within said cylinder, a reciprocating cylinder having its end beveled to fit to the beveled wall of the stationary cylinder and form a close joint therewith, a plunger mounted in the reciprocating cylinder, and means whereby when the reciprocating cylinder recedes from the stationary cylinder the block in the latter cylinder will be actuated to eject a brick formed therein.

In testimony whereof I affix my signature.
SWAN E. MOREN. [L. s.]
